[57] CLAIM

The ornamental design for a vertical blind valance, as shown and described.

DESCRIPTION

FIG. 1 is a perspective view of a vertical blind valance showing my new design;

FIG. 2 is a front elevational view thereof;

FIG. 3 is a plan view thereof;

FIG. 4 is a rear elevational view thereof;

FIG. 5 is a bottom elevational view thereof;

FIG. 6 is a right side elevational view thereof; and,

FIG. 7 is a left side elevational view thereof.

FIGS. 1-5 are shown broken away to indicate indeterminate length, it being understood that the design continues uniformly along any length.

The broken line illustration of vertical blinds in FIGS. 1, 2, 4, 6, and 7 is for illustrative purposes only and form no part of the claimed design.
